SHOEMAKING METHOD

Fred Maccarone and Harry L. Sutcliffe, Brooklyn, N. Y., assignors to The Del-Mac Shoe Process Corporation, New York, N. Y.

Application March 30, 1935, Serial No. 13,873

11 Claims. (Cl. 12—146)

Our invention relates to shoes and shoe making, and particularly to methods of making shoes in which the insole and outsole components are divisions of a common blank, and the insole is 5 channeled to provide a channel leaf for stitch lasting or an integral lip or rib whereby the shoe upper may be side lasted in relation to the insole. Heretofore, where the blank has been divided to obtain an insole and an outsole of proper 10 weights for the finished shoe, it has been found that the insole member was so light as to require the exercise of great care and skill in properly performing the subsequent channel cutting operation, and this has been found particularly true 15 where the insole division of the blank is skeletonized over the forepart, and therefore weaker and less capable of standing up under the subsequent channeling operation. Because of this, it has been usual to divide the blank so as to obtain 20 an insole substantially heavier than is necessary or desirable for the finished shoe, and the outsole has thereby been unduly reduced in weight.

The principal object of our invention, therefore, is to provide an improved method in accordance 25 with which the insole is defined and channeled in a full weighted sole blank before the blank is divided into insole and outsole parts, each part having proper proportionate weight for the finished shoe.

30 Another principal object is to provide an improved method having the foregoing advantages in which the insole channel leaves, integral lip or rib members, may be positioned in relation to the edge of an insole predefined and preformed 35 in the full weighted sole blank.

A further object is to provide an improved method having the foregoing advantages which may be practiced by the use of conventional shoe making machinery, and other and further objects 40 will appear from the following specification.

Referring to the drawings:

Figure 1 is a plan view of a rounded sole blank having an incision formed therein to define the contour of an insole.

45 Figure 2 is a cross sectional view taken on line 2—2 of Fig. 1.

Figure 3 is a sectional view similar to Fig. 2 showing the channel cuts formed in the blank and the waste portion removed in the course of 50 the channeling operation.

Figure 4 is a sectional view illustrating the manner in which the blank is divided to provide the properly sized and channeled insole member and an outsole member.

55 Figure 5 is a plan view of the insole member

showing the channel leaves erected and secured together to form a lip.

Figure 6 is a cross sectional view taken on line 6—6 of Fig. 5.

Figure 7 is a plan view of the outsole member. 5

Figure 8 is a plan view of a sole blank similar to the blank shown in Fig. 1, in which the insole member has been defined and initially formed by the removal of a triangular rand.

Figure 9 is a cross sectional view taken on line 9—9 of Fig. 8 and shows the rand removed in performing the insole and the condition of the sole blank after such removal.

Figure 10 is a cross sectional view similar to Fig. 9 and illustrates the blank having the channel 15 cuts formed therein.

Figure 11 is a cross sectional view illustrating the manner in which the blank may be divided to obtain a fully formed and channeled insole having an aperture in the ball portion thereof, 20 and an outsole member having a projection at its ball portion adapted to register with the insole aperture.

Figure 12 is a plan view of the insole member shown in Fig. 11 after the channel leaves have 25 been erected to form a lip.

Figure 13 is a cross sectional view of the insole taken on line 13—13 of Fig. 12.

Figure 14 is a plan view of the outsole member shown in Fig. 11.

20 indicates a full weighted sole blank having a thickness corresponding to the combined thickness of the desired insole and outsole and rounded to the configuration of an outsole. The blank has a cut or incision, 21, formed therein which defines the configuration of the desired insole and extends inwardly from a face of the blank a distance corresponding to the thickness of the desired insole. The cut or incision, 21, may be formed in the blank in accordance with the method taught in United States Patents #1,988,282 and #1,988,283, issued to applicant, Fred Maccarone, January 15, 1935, but more preferably as taught in the pending application of said Fred Maccarone, Serial No. 711,673, filed February 17, 1934. 45

Channel cuts, 22 and 23, are then formed in the blank in the usual manner and by means of the usual equipment, the channel cut, 23, extending angularly from the same surface of the blank as does the incision, 21, and spaced inwardly 50 from said incision as illustrated. The channel cut, 22, intersects the incision, 21, and is, of course, parallel with the cut, 23. In the course of this channel cutting operation, a light marginal waste rand, 24, is removed, said rand com- 55

prising material lying outwardly of the incision, 21, and channel leaves, 25 and 26, are defined, as will be readily understood.

The sole blank thus prepared is then split with-
5 in the depth of the incision, 21, along line $x-x$ of Fig. 3 to divide the blank into a separate out-
sole portion, 27, and a properly sized insole portion, 28, carrying the integral channel leaves or
lip members, 25 and 26, respectively. In the
10 course of the splitting operation, a waste rand,
29, results, comprising the material remaining
outside of the incision, 21, and above the line of
split. The insole, 28, formed and obtained as
above described, may then be attached to a last
15 where it is desired to make stitch-lasted shoes
in which the upper is secured in lasted relation
to the insole by means of thread extending
through the overlasted portions of the upper and
through the insole material lying between the
20 channel cuts, 25 and 26. Where it is desired to
make shoes with side-lasting methods in which
an integral lip or rib member is required, the
members, 25 and 26, are erected and adhesively
secured together to provide the desired lip, 30,
25 as shown in Figs. 5 and 6, to which the upper
may be stapled or otherwise secured. Where the
upper is lasted to the lip, 30, it is quite usual,
although not absolutely essential, to reinforce
the insole and the lip by means of a flanged
30 layer of properly shaped fabric (not shown) in
accordance with the popular "economy" method.

We desire to point out here that although we
prefer to define the edge of the insole by forming
the cut, 21, in the full weighted sole blank, this
35 step is not absolutely essential to our invention,
broadly considered, and the split-off insole, 28,
may be rounded or otherwise trimmed to size
after the sole blank has been divided into the
insole and outsole parts. However, such an oper-
40 ation would be attended by difficulties because
such subsequent insole rounding operation would
have to be performed in relation to the channel
cuts, 22 and 23, and, as the use of the usual
rounding machine requires that the sole member
45 be clamped between patterns, it would be difficult
to properly position the insole in the machine so
that the patterns will bear proper relation to the
channel cuts.

The method practiced as above described will
50 be found to produce satisfactory sole members
in all cases where the edge of the outsole and
the edge of the smaller insole member are par-
allel. However, it often happens that the edge
55 contour of the insole differs materially from the
contour of the outsole edge, and where that is
the case, it is not practical to space the channel
cuts, 22 and 23, in relation to the outsole rounded
edge of the blank. To meet this situation, we
60 have provided a modification of our method in
accordance with which we define the insole edge
by an incision or cut, 21', which defines and forms
the edge of the insole member, and also an angu-
lar cut, 31, which extends from the face of the
65 blank inwardly and meets the cut or incision,
21', at a point at or just above the bottom of
said incision.

The cuts, 21' and 31, may be made with one
or two knives and in one or more operations, de-
70 pending upon the tools and equipment available
at the factory where the shoes are to be made.
We contemplate that these cuts may be made in
the same operation in which the outsole config-
uration is imparted to the full weighted blank in
75 accordance with the principles taught in the co-

pending application of Fred Maccarone, Serial
No. 711,673, above referred to.

The making of the cuts, 21' and 31, results in
a rand-like waste portion, 32, and the formation
of a notch-shaped groove, 33, the inner wall of
5 which forms the edge, 35, of the insole, 34. The
full weighted blank is then channeled in the
same manner and by the same means as above
described except that the position of the channel
cuts, 22' and 23', may be gauged from the insole 10
edge, 35, instead of from the outsole rounded
edge of the blank. The blank thus prepared may
then be divided as previously described to obtain
an imperforate insole member.

We have found that there is distinct advantage 15
in positioning the inclined cut, 31, inwardly of
the edge of the sole blank so that the edge thick-
ness of the blank is not reduced, thus facilitating
proper splitting at the marginal portions of the
blank when the blank is divided into insole and 20
outsole parts by the preferred method of splitting.

We have illustrated in Fig. 11 how the sole
blank may be divided along line $x-x$ of Fig. 10
to obtain an outsole, 36, centrally elevated in
thickness over the central area of its ball por- 25
tion, and a perfectly sized and channeled insole
having an opening in the ball portion thereof cor-
responding to said outsole elevation, the margins
of the elevated area of the outsole being beveled
on a long angle. In dividing the sole blank in 30
this manner, we prefer to follow the principles
taught in United States Patent #1,988,231, grant-
ed to Fred Maccarone January 15, 1935, wherein
a method is disclosed in accordance with which
a sole blank, having a thickness equal to the 35
combined thickness of the insole and outsole de-
sired, is temporarily distorted by inflexing or
depressing it over areas corresponding to the
skeletonized portions of the desired insole so
that such portions will avoid the blade of a 40
splitting machine by means of which the blank
is divided. However, we are aware that there are
other methods of dividing the blank to obtain
sole members of substantially the same construc- 45
tion if for any reason it may be desired to prac-
tice such other methods.

The insole, 34, may be employed for stitch-
lasted shoes, or the leaf members, 25' and 26',
50 may be erected and cemented together to form a
lip, 30', for side-lasting methods similarly as the
insole, 28.

After the upper has been lasted and secured to
the insole and such further operations as may
be necessary preparatory to laying the outsole
have been performed, an outsole is secured in
proper relation to the insole member by stitching
or cementing to the overlasted portions of the
upper and to the insole, and where a welted
construction is desired, to the outwardly extending
55 portions of a welt. Our method lends itself very
well to the production of welt shoes, the welt be-
ing secured to the insole lip in accordance with
common practices which form no part of this
invention, and which we have not deemed it neces-
sary to describe.

It will be apparent that because the channel
cuts extend inwardly from a surface of the full
weighted blank, and because the insole is bot-
tomed on the last with its channeled surface
outward, that when the outsole is laid and as-
sembled, the facing surfaces of the insole and
outsole will not be the divided surfaces of the
blank. However, inasmuch as shoes are made
in mated pairs, it will be apparent that the in-
sole obtained from the blank rounded for the 75

right foot will be used for making the left shoe, and vice versa.

It might appear from the drawings, which are greatly exaggerated for the purposes of this disclosure, that some difficulty would be experienced in carrying out this practice where the construction embodies the skeleton insole, 34. However, the beveled margins, 40, of the insole opening are in fact very light and flexible and readily take the position indicated in dotted lines of Fig. 13, whereby they are adapted to meet flush with the beveled shores of the island-like outsole elevation so smoothly that it is difficult to discover by simple observation on which side of the insole the bevel is formed, with the result that the interior of the finished shoe is so smooth and flush as to be indistinguishable from shoes in which the divided portions of the same sole blank are assembled together.

Having thus described our invention, we claim:

1. In shoe making methods wherein a sole blank is divided to obtain an insole and an outsole, that improvement which includes forming a channel leaf integral with the insole portion of the blank and then dividing the blank.

2. In shoe making methods, that improvement which includes providing a rounded outsole blank having an inward cut therein defining the edge of an insole, said cut extending to a depth corresponding to the thickness of a desired insole, then channeling the insole portion of the blank, and thereafter dividing the blank within the depth of said cut to obtain an outsole and a properly sized and channeled insole.

3. In shoe making methods wherein a sole blank is divided to obtain an insole and an outsole, that improvement which includes forming a cut in the blank to define the edge of the desired insole, channeling the blank in relation to the insole edge thus defined, and then dividing the blank.

4. In shoe making methods wherein a sole blank is divided to obtain an insole and an outsole, that improvement which includes forming a cut in the blank to define the edge of the desired insole, said cut extending to a depth corresponding to the thickness of the insole desired, channeling the insole portion of the blank in relation to the insole edge thus defined, and dividing the blank within the depth of said cut to obtain an outsole and a properly sized and channeled insole.

5. In shoe making methods wherein a sole blank is divided to obtain an insole and an outsole, that improvement which includes forming a groove in the blank said groove extending to a depth corresponding to the thickness of the insole desired and having a wall thereof defining the desired insole edge, channeling the insole portion of the blank in relation to said wall, and dividing the blank within the depth of said groove to obtain an outsole and a properly sized and channeled insole.

6. In shoe making methods wherein a sole blank is divided to obtain an insole and an outsole, that improvement which includes forming a channel

leaf integral with the insole portion of the blank before it is divided, dividing the blank into insole and outsole portions, and erecting said channel leaf to form a lip whereby the upper of the shoe may be attached.

7. In shoe making methods wherein a sole blank is divided to obtain an insole and an outsole, that improvement which includes providing a rounded sole blank having an inward cut therein defining the edge of an insole, said cut extending to a depth corresponding to the thickness of the desired insole, forming a channel leaf integral with the insole portion of said blank, and dividing the blank within the depth of said cut to obtain a properly sized insole having said leaf integral therewith.

8. In shoe making methods wherein a sole blank is divided to obtain an insole and an outsole, that improvement which includes providing a rounded sole blank having an inward cut therein defining the edge of an insole, said cut extending to a depth corresponding to the thickness of the desired insole, forming a channel leaf integral with the insole portion of said blank, dividing the blank within the depth of said cut to obtain a properly sized insole having said leaf integral therewith, and erecting said leaf to provide a lip whereby the upper of the shoe may be attached.

9. In shoe making methods wherein a sole blank is divided to obtain an insole and an outsole, that improvement which includes forming a groove in the blank to define an insole, the inner wall of said groove forming the edge of the insole desired, forming a channel leaf in the insole portion of the blank inwardly of said groove and gauged in relation to said wall and thereafter dividing the blank in a plane within the depth of the groove to obtain an outsole and a properly sized insole, said insole having an integral channel leaf carried thereby.

10. In shoe making methods wherein a sole blank is divided to obtain an insole having an opening in its forepart and an outsole having a projection corresponding to said insole opening, that improvement which includes forming a cut in the blank, to define the edge of the desired insole, said cut extending to a depth corresponding to the thickness of the insole desired, channeling the insole portion of the blank in relation to the insole edge thus defined, and dividing the blank within the depth of said cut to obtain an outsole and a properly sized and channeled insole.

11. In shoe making methods wherein a sole blank is divided to obtain a skeletonized insole and a complemental outsole, that improvement which includes channeling the insole portion of the blank, and dividing the blank to obtain an outsole having a projection thereon and a channeled insole having an opening therein to receive said projection, said insole and outsole being counterparts.

FRED MACCARONE.

HARRY L. SUTCLIFFE. 65
